UNITED STATES PATENT OFFICE.

JAMES L. CUNNINGHAM, OF WILMINGTON, DELAWARE.

DRINKING-FOUNTAIN ATTACHMENT.

1,142,675.

Specification of Letters Patent. Patented June 8, 1915,

Application filed September 5, 1914. Serial No. 860,421.

To all whom it may concern:

Be it known that I, JAMES L. CUNNINGHAM, a citizen of the United States, residing at Wilmington, in the county of New Castle and State of Delaware, have invented new and useful Improvements in Drinking-Fountain Attachments, of which the following is a specification.

This invention relates to drinking fountains, and particularly to a sanitary guard for a fountain of this class, and the primary object of the same is to provide means in connection with the water outlet of a drinking fountain to prevent contact of the lips, chin, beard or any part of the face of the user with said outlet when drinking, to avoid disease germ and uncleanly contamination in any manner of the water outlet or parts adjacent thereto, and thereby preserve drinking fountains in a perfectly sanitary and safely usable condition.

The invention consists in the preferred construction and arrangement of parts which will be more fully hereinafter described and claimed.

In the drawing: Figure 1 is a side elevation of a drinking fountain embodying the features of the invention. Fig. 2 is a front elevation of the improved guard attachment particularly embodying the features of the invention. Fig. 3 is a transverse vertical section on the line 3—3, Fig. 2.

The numeral 5 designates a water supply connection or pipe having a suitable valve 6 which will be provided with any preferred form of device for engagement with the valve stem end 7 for controlling the flow of the water through the connection. The supply connection or pipe 5 is shown as projecting outwardly from a wall or upright support 8, but such disposition of the connection or pipe may be modified at will. Below the connection or pipe 5 is a catch basin or open tank 9 into which the unused water flows or falls, and attached to the bottom of this basin or tank is a drain pipe 10 that may run to and connect with any suitable form of waste pipe or other analogous device.

The improved attachment is particularly shown by Figs. 2 and 3 and consists of a lower tubular elbow 11 having an internally screw-threaded extremity 12 for attachment to the outer end of the connection or pipe 5, and rising from the outer portion of this elbow is an upright having a jet outlet or water supply exit 13. Extending outwardly in

flaring curved lines and in opposite directions from the jet outlet or water supply exit 13 are guard arms 14 of equal length and terminating in convex or spherical heads 15. 60 These guard arms 14 are integrally formed with opposite portions of the jet outlet, water supply exit or nozzle 13 at a distance from the free end of the latter so that the water has free pressure expulsion from the said outlet. The guard arms 14 have a fixed position relatively to the jet outlet or water supply exit 13, the said arms being independent of the valve 6 so far as the operation of the latter is concerned. It is desired 70 that the terminals of the arms 14 always have a predetermined distance from the jet outlet or water supply exit 13 to prevent the user from reaching the outlet or supply exit with the lips, and, moreover, it will be seen 75 that the jet outlet, water supply exit or nozzle 13 and the arms 14 are preferably slightly inclined outwardly, as clearly shown by Fig. 1, relatively to a perpendicular line so that the water will flow over toward the 80 front after passing upwardly between the guard arms.

When drinking from the fountain embodying the improved guard attachment, the user disposes his mouth between and preferably a short distance above the heads 15 of the arms 14 and takes the water expelled outwardly between the said arms, and too close approach to the jet outlet, water supply exit or nozzle 13 is prevented by the spherical heads striking the cheeks of the user, the arms 14 being of such length and distance apart as to defeat any attempt to engage the lips or any part of the face of the user with the end of the jet outlet, water supply exit or nozzle 13. Moreover, the water is expelled between the arms 14 and not from the latter, and does not touch the arms and is not retained adjacent to the arms, but falls below in the catch basin 9 from which it is rapidly drained by the pipe 10. In addition, an individual drinking cup or other vessel can be filled from this attachment, thus making it unnecessary to have other connections, valves, etc., for the purpose of filling such cups or vessels.

The angle or flare and general proportions and dimensions of the arms 14 may be varied at will. It is preferable that the water be expelled from the jet outlet, supply exit or nozzle 13 with such force that it may be conveniently reached by the user without

resting his cheeks against the heads 15, but the expulsion force of the water may be less forceful so that the user can rest his cheeks against the said heads with equal efficiency 5 in the function of the guard attachment. The water outlet jet or nozzle 13 is shown arranged to direct the water upwardly, and the arms 14 and heads 15 are correspondingly arranged, but it will be understood 10 that the jet or nozzle 13 might be arranged to expel the water in a horizontal plane or at an angle to a horizontal plane.

From the foregoing it will be seen that no part of the face of the user of the improved 15 attachment comes into contact with the latter except portions of the opposite cheeks which bear upon the free ends of the arms 14, the chin and nose being clear of any part of the attachment. The arms 14 are of such 20 preferred length that it will be impossible to engage the outlet nozzle or water supply exit 13 with the lips. Therefore, the improved attachment is exceptionally sanitary in its use by reason of the fact that contamination of parts of the same is reduced to a 25 minimum and also the structure is simplified and the cost of manufacture and application is also materially reduced. Another advantageous feature of the improved attachment 30 is that it may be readily applied to any water supply means without modifying the structure of the latter or making any changes in the attachment to adapt the same to different applications.

The improved attachment is simple in construction, can be cheaply manufactured from any suitable material, and can be readily applied to any drinking fountain supply pipe or connection having a suitable 40 screw-threaded end, or the attachment can be connected to a water supply pipe by any means adapted to practically secure or fix it thereto.

What is claimed is:—

1. A drinking fountain attachment, comprising an outlet nozzle having means for attachment to a water connection, and independent diverging guard arms attached, respectively, at their lower extremities to 50 diametrically opposite portions of the nozzle and having their upper extremities projecting above the nozzle, the upper extremi-

ties of said arms adapted to engage the cheeks of the user and remaining during the drinking act at substantially the same distance from the supply connection and the outlet of the nozzle to obviate contact of any other part of the face of the user with the attachment and all contact with the nozzle. 55

2. A drinking fountain attachment comprising an outlet nozzle having means for attachment to a supply connection and provided with a passage for the constant flow of water therethrough and upwardly therefrom and guard arms attached to opposite portions of said nozzle and extending equally outwardly and upwardly therefrom and having unconnected extremities for engagement with the cheeks of the user; said guard arms remaining constantly at the same elevation above the supply connection. 60

3. A drinking fountain attachment comprising an outlet nozzle having means for attachment to a supply pipe and a passage for the constant flow of water therethrough, 75 and guard arms secured to said nozzle and extending laterally and upwardly therefrom for engagement with the cheeks only of the user to obviate contact of any other part of the face of the user with the attachment and all contact with the nozzle, the free ends of said arms remaining during the drinking act at the same distance above the supply connection. 80

4. A drinking fountain attachment comprising an outlet nozzle forming part of a connection for engagement with a water supply pipe, guard arms integrally formed with opposite portions of the nozzle and extending outwardly from the latter and 90 having free unconnected extremities for engagement with the cheeks of the user at such a distance from the nozzle as to obviate contact of any other part of the face of the user with the attachment and all contact with the nozzle. 95

In testimony whereof I have heretinto set my hand in presence of two subscribing witnesses.

JAMES L. CUNNINGHAM.
